CLAIM

The ornamental design for a bezel for wheeled luggage towing handle, as shown and described.

DESCRIPTION

FIG. 1 is a perspective view taken from in front of and above of a bezel for wheeled luggage towing handle according my new design;

FIG. 2 is a top plan view thereof; and,

FIG. 3 is a front elevational view thereof.

The bottom, both ends, and the rear aspects of the bezel are hidden from view in normal use and form no part of the claimed design.
